UNITED STATES PATENT OFFICE.

JOHN J. RUSSELL, OF NEW YORK, N. Y.

DEVICE FOR FASTENING RAILS TO TIES.

No. 923,708.

Specification of Letters Patent.

Patented June 1, 1909.

Application filed May 26, 1908. Serial No. 435,045.

To all whom it may concern:

Be it known that I, JOHN J. RUSSELL, a citizen of the United States, residing at New York, in the county of New York and State 5 of New York, have invented new and useful Improvements in Devices for Fastening Rails to Ties, of which the following is a specification.

This invention relates to railroad track 10 construction, and more particularly to devices for fastening the rails of a track to the cross ties.

The invention has for one of its objects to provide a comparatively simple, inexpensive 15 and substantial rail fastening device intended more particularly for use in connection with metal cross ties such for instance as those of I-beam construction.

A further object of the invention is the 20 employment of two or more fastenings having terminal lugs for engaging opposite sides of the rail bases for preventing lateral movement of the rails, one lug of each fastening being in the shape of a hook that overlaps 25 the base of a rail for clamping the latter to the cross tie.

Another object is the provision of a tie 30 having a pair of apertures for each fastening arranged to coincide with the edges of the 35 base of the rail and into which apertures the lugs of the fastening project for engagement with the rail base, the fastening being locked in position by the hooked-shaped lug at one end engaging the rail base and a wedge-shaped split key or the like securing or locking 40 the lug at the opposite end.

With these objects in view and others, as 45 will appear as the description proceeds, the invention comprises the various novel features of construction and arrangement of parts which will be more fully described hereinafter and set forth with particularity in the 50 claims appended hereto.

In the accompanying drawing, which illustrates one of the embodiments of the invention, Figure 1 is a perspective view of a portion of a tie and rail equipped with the improved fastening devices. Fig. 2 is a transverse section taken through a rail at the joint 55 between two sections, and showing one of the fastening devices in elevation. Fig. 3 is a transverse section of a rail and tie with the fastening device in final position, as shown by full lines, and in various steps during the

insertion or removal of the device as shown 55 by dotted lines. Fig. 4 is a perspective view of one of the fastening devices. Fig. 5 is a fragmentary plan view of one end of an I-beam tie. Fig. 6 is a perspective view of one 60 of the wedge-shaped keys.

Similar reference characters are employed to designate corresponding parts throughout the several views.

Referring to the drawing, A designates a 65 steel or other cross tie which may be of I-beam or other cross section. The top of the tie is provided with vertical apertures 1 and 2 that are spaced apart so as to lie at opposite sides of the base 3 of the rail B. In the present instance, two pairs of openings are 70 provided in the tie at each end so as to receive two fastenings C, although any other number of fastenings may be employed. Each fastening comprises a single piece of 75 metal formed into a bar-shaped body or shank 4 and substantially parallel lugs 5 and 6 at the end of the body and extending from the same side thereof. The lug 6 has its extremity formed into a hook 7 that is adapted to engage the top of the rail base, while the 80 lug 5 has slightly rounded sides 8 so as to pass vertically into and out of the opening 2, Fig. 3, and is formed with an aperture 9 for receiving a wedge-shaped split key 10 or equivalent securing means. The openings or 85 slots 1 of the tie are enlarged at 11 so as to provide ample clearance for the fastening to be turned at a certain point in the placing and removing of the fastening, and the shank or body 4 of the fastening is formed 90 with a fulcrum 12 which bears under the top of the tie and causes the hook 7 to be drawn tightly against the rail base when the wedge-shaped split key is inserted, thus securely holding the rail to the tie. The lugs 5 and 6 95 of each fastening serve to prevent lateral displacement of the rail, while the hooks 7, which are reversely disposed to engage the opposite sides of the rail, serve to prevent the rail from vertical displacement.

In securing a rail to the cross ties at the joints of the rail sections, the angle splices D have their base-engaging flanges 13 notched at 14, Fig. 2, for receiving the hook-shaped lugs 6 as at present notched to receive 105 a spike, the said lugs being a little higher than those of the fastenings intended to secure the rails to the ties at points intermed-

ate the joints, owing to the additional thickness of the base-engaging flange 13 of the angle splice.

In constructing a track in accordance with the present invention, the cross ties A are laid in the roadbed in the usual manner, care being exercised to arrange the ties so that the apertures 1 and 2 thereof will be even with the bases of the rails. The rail sections 10 are then placed on the ties and brought into proper relation with the apertures 1 and 2 so that the fastenings C can be inserted. In inserting a fastening, the same is held in such a position as to introduce the straight lug 5 15 into the aperture 1 from the top of the tie, as shown by the dotted line position *a*, Fig. 3. The fastening is lowered until the narrowest part of the shank thereof is in the opening 1, whereupon the fastening is reversed to the dotted line position *b*, so that by further lowering the fastening and swinging it under the top web of the tie to a horizontal position the hook will engage the base of the rail 20 and the lug 5 enter the aperture 2. The wedge-shaped split key 10 is then driven into the hole of the lug 5 for locking the fastening in position. The next fastening is inserted in the same manner except that the hook-shaped lug will be at the opposite side of the rail. It will thus be seen that the rails can be fastened to the ties or unfastened in a simple and expeditious manner and the rails are firmly secured in position so that spreading is effectively prevented.

From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device

shown is merely illustrative, and that such changes may be made when desired as are within the scope of the appended claims.

Having thus described the invention, what I claim is:—

1. The combination of a cross tie having spaced apertures, a rail resting on the tie with the edges of its base coincident with the apertures, a fastening consisting of a body portion disposed under the tie and of such length as to extend from one aperture to the other and having its ends formed respectively into an upwardly-extending apertured lug and an upwardly-extending rail-engaging hook disposed with its bill projecting toward the lug, said lug and hook being disposed normally in the apertures of the tie, the aperture in which the hook is contained being of such size as to permit the fastening to be applied or removed through the same and to be turned therein, and a locking pin passing through the apertured lug and bearing on the top surface of the tie for holding the fastening in place.

2. The combination of a cross tie having a horizontal portion provided with spaced apertures, a rail resting on the horizontal portion and disposed between the apertures, a fastening applied to the tie by insertion and removal through one of the apertures and provided with straight and hook-shaped lugs at opposite ends respectively extending through the apertures and engaging the base of the rail and having a fulcrum bearing against the under side of the said horizontal portion of the tie, and a device secured to the straight lug for holding the fastening in position.

In testimony whereof I affix my signature in presence of two witnesses.

JOHN J. RUSSELL.
